UNITED STATES PATENT OFFICE.

HJALMAR LINDESTROM, OF CHICAGO, ILLINOIS, ASSIGNOR TO MARIA LAVISA LINDESTROM, OF SAME PLACE.

MOWER.

SPECIFICATION forming part of Letters Patent No. 427,238, dated May 6, 1890.

Application filed November 11, 1889. Serial No. 329,927. (No model.)

To all whom it may concern:

Be it known that I, HJALMAR LINDESTROM, a citizen of the Kingdom of Sweden and Norway, and a resident of Chicago, in the county 5 of Cook and State of Illinois, have invented certain new and useful Improvements in Mowers; and I do hereby declare that the following is a full, clear, and exact description thereof, reference being had to the accompanying drawings, and to the letters of 10 reference marked thereon, which form a part of this specification.

This invention relates to novel improvements in mowers; and it consists in the features of construction and combinations of parts hereinafter fully described, and pointed out in the appended claims.

In the accompanying drawings, Figure 1 is a top plan view of a mower constructed in accordance with my invention, showing only a portion of the cutter-bar. Fig. 2 is a vertical sectional view on the line 2 2 of Fig. 1. Fig. 3 is a front elevation of the same. Fig. 4 is a detail perspective view of the reciprocating pawl. Fig. 5 is a detail perspective view of a portion of the supporting-frame, illustrating the bearing for the vibrating bell-crank, said figure comprising two parts. Fig. 6 is a detail perspective view of the vibrating bell-crank.

In said drawings, A A indicate the wheels of a mower rigidly attached to the ends of an axle A', which latter supports the working parts of the machine.

B indicates a supporting-frame, having a forwardly-projecting portion or trunnion b and two rearwardly-extending and upwardly-deflected arms b' b², said arms b' b² being provided in their rear ends with bearing-apertures, through which the axle A' passes, and by means of which said frame B is supported. The said arm b² is provided with a horizontal transverse portion b³, which stands at right angles to the arm b'.

a indicates a seat for the driver, suitably connected with the arm b² of the said frame, and a' indicates the draft-beam of the machine.

C indicates a cutter-bar of the usual construction, having a shoe C', provided with an uprising portion in the form of a sleeve c,

which is secured upon the trunnion b of the supporting-frame.

C² is a pitman pivoted at one end to the inner end of the cutter-bar, and provided in its other end with a ball-socket, as shown at c'. The said pitman serves to communicate a reciprocatory movement to the cutter-bar. Reciprocatory motion is given to said pitman by means of a vibrating bell-crank lever D, pivoted to the supporting-frame B. The said lever D has a forwardly-projecting long arm d', provided at its end with a ball d², which ball is secured within the socket c' of the pitman. The short arm d³ of said lever D projects laterally, and is provided on its end with a ball d⁴, which ball is secured within a ball-socket e upon a reciprocating double pawl E, hereinafter referred to. The said lever D is provided at the meeting-point of its arms with two studs d⁵ d⁶, located, respectively, on the upper and lower faces thereof. Just in the rear of the portion b³ of the arm b² and on the arm b' a lug b⁵ is cast or otherwise secured thereto. Said lug b⁵ is provided with a bearing-aperture b⁶, into which the stud d⁶ upon the lever D is inserted.

B' is a block or plate, having a base portion b⁷ and an overhanging lug or projection b⁸, said lug b⁸ being provided in its under face with a bearing-aperture b⁹, into which the stud d⁵ on the lever D is inserted. The distance between the under face of the lug b⁸ and the bottom of the base b⁷ is equal to the thickness of the lever D at the base of the studs, so that when the said lever is pivoted between the block B' and lug b⁵ it will have a firm and easy bearing therein.

As shown in Fig. 5, the block B' is provided with bolt-holes b¹⁰, which register with bolt-holes b¹¹ upon the arm b', whereby said block can be secured thereto.

The devices for giving a reciprocatory motion to said bell-crank lever D comprise a ratchet-wheel A² and a double pawl or ratchet E, before mentioned. The said ratchet-wheel A² is loosely mounted upon the axle A', but can be made to turn therewith by means of any suitable clutch mechanism, as shown at a², and an operating-lever a³, located within reach of the driver. The teeth of said wheel A² are so formed that their abrupt or radially-

arranged faces will always be in advance of their inclined faces when the wheel is revolved by the forward movement of the machine. It is found convenient to face the said teeth 5 with removable pieces of steel, as shown at a^4 a^4 , so that when the teeth are worn they can readily be repaired by the insertion of new pieces. Furthermore, the wheel can be made of a metal of reduced cost as compared with 10 that used if the teeth were of the same metal as the rest of the wheel. The said ratchet-wheel A^2 is provided on both sides with annular concentric depressions, forming the shoulders A^3 A^3 , the diameter of the wheel at 15 said shoulders being somewhat less than the diameter at the pitch-line of the teeth.

The double pawl E, before referred to, is forked or provided with two arms E' and E^2 , the distance between the outer ends of which 20 is equal to the diameter of the annular shoulders A^3 A^3 . E' is the upper or short arm, while E^2 is the lower or long arm, as will be described. The end portions of each of the 25 said arms E' E^2 are slotted vertically to form fingers e' e' and e^2 e^2 , the distance between said fingers being sufficient to permit them to pass on either side of the ratchet-wheel and rest upon the annular concentric shoulders A^3 A^3 .

30 E^3 indicates a guide-finger or pin located upon the forward end of the pawl, and entering a guide-bearing B^2 , located upon the horizontal portion b^3 of the arm b^2 of the supporting-frame. It is obvious that the engagement 35 of the fingers of the arms E' E^2 with the annular shoulders serves to guide the rear portion of said pawl when the guide-finger guides the front end in an obvious manner.

The arm E' is provided at the rear portion 40 of the fingers e' and on its upper face with a transversely-arranged detent-piece e^3 , secured in uprising lugs e^4 e^4 , formed thereat. The said lugs are provided with registering transverse openings, through which the detent-piece 45 e^3 is passed and secured by set-screws e^5 e^5 , in the usual manner. The lower arm E^2 is provided near the forward end of the fingers e^2 , and upon their lower faces, with a transversely-arranged detent-piece e^6 , secured in 50 depending lugs e^7 e^7 , formed thereat. The said lugs are provided with registering transverse openings, through which the said detent-piece e^6 is passed and secured by set-screws e^8 e^8 , in an obvious manner. From the foregoing description 55 it is obvious that the said detent-pieces e^3 e^6 can be easily removed and replaced when worn out, and, being rectangular in cross-section, they can be turned around to present an unworn edge; or a new piece can be furnished with very little trouble or expense, owing to the simple form of the piece.

The operation of my invention is as follows: Upon reference to Fig. 2 it will be seen that the detent-piece e^3 stands in front of 60 and over the ratchet-wheel, while the detent-piece e^6 is located beneath and in the rear of the wheel. The fingers e' e^2 are constantly in

contact with the annular shoulders A^3 . The said double pawl is shown at the backward limit of its movement, or, more properly, just 70 commencing to move forward. Said reciprocating pawl has a range of movement equal to one-half of the distance between the points of two adjacent teeth. For instance, we will assume that the teeth are two inches apart. 75 Then the reciprocating double pawl will have a movement of one inch. In said Fig. 2 it will be noted that the detent e^6 is held from engagement with the teeth of the ratchet-wheel by reason of the fingers e^2 resting against 80 the annular shoulder A^3 . The detent e^3 being engaged by the ratchet-wheel, said pawl E will be moved forwardly as said ratchet-wheel revolves. The detent e^6 will move forwardly, and consequently come nearer to the center of the wheel, as the fingers slide over the shoulder A^3 . The fingers e' resting upon the shoulder A^3 , it is evident that the detent-piece e^3 will be moved away from the center of the wheel as the pawl E is moved forwardly, and hence said detent-piece e^3 will be disengaged from the ratchet-wheel, and such disengagement takes place simultaneously 90 with the engagement of the detent e^6 with the ratchet-wheel. When said detent e^6 is engaged with the ratchet-wheel, the pawl E will be moved backwardly, and the reverse of the foregoing operation is performed—namely, the detent e^6 is gradually disengaged from the wheel while the detent e^3 is thrown into engagement therewith. It is obvious that as a tooth moves toward the detent-piece while the detent-piece is carried toward the tooth at the same rate of speed they will meet half-way, and consequently the pawl moves but 95 one inch in either direction. It follows from the foregoing that the pawl will be reciprocated as the said ratchet-wheel is turned. The reciprocating movement of said pawl E is imparted to the cutter-bar by means of the bell-crank lever D and pitman C², as before described. By means of the lever a^3 and clutch mechanism it is manifest that the ratchet-wheel can be disconnected from the axle, so as not to turn therewith. 110

I claim as my invention—

In a mower, the combination, with the driving-wheels, supporting-frame, and cutter-bar, of a ratchet-wheel mounted on the driving-wheel shaft and adapted to receive rotary motion therefrom, two annular concentric shoulders located one on either side of and each having a diameter less than that of said ratchet-wheel, a double pawl mounted in sliding bearings upon said supporting-frame, and having a motion toward and from said ratchet-wheel in a straight line, said pawl comprising two arms having bifurcated end portions embracing said ratchet-wheel and resting in contact with said shoulders, each of said bifurcated end portions being provided on their outer faces with lugs, as e^4 e^4 e^7 e^7 , having registering openings, within which are removably secured detent-pieces, as e^3 e^6 , said 120 125 130 135

detent-pieces being so located as to engage the ratchet-wheel at points diametrically opposite, and mechanism, substantially as described, connecting said double pawl with the 5 cutter-bar, whereby the reciprocating movement of the former is imparted to the latter, all substantially as set forth.

In testimony that I claim the foregoing as my invention I affix my signature in presence of two witnesses.

HJALMAR LINDESTROM.
